[57] CLAIM

The ornamental design for a securing device for catheter, as shown and described.

DESCRIPTION

FIG. 1 is a perspective view of one side of a securing device for catheter, showing my new design;

FIG. 2 is a view similar to FIG. 1, but showing the opposite side thereof; and

FIG. 3 is a cross-sectional view taken on the line designated by the arrows in FIG. 1.

FIG. 1

FIG. 2

FIG. 3
